UNITED STATES PATENT OFFICE.

ORRELL ASHTON, OF LAWRENCE, MASSACHUSETTS, ASSIGNOR TO UNITED SHOE MACHINERY COMPANY, OF PATERSON, NEW JERSEY, A CORPORATION OF NEW JERSEY.

ASSEMBLING-MACHINE.

No. 893,696.

Specification of Letters Patent. Patented July 21, 1908.

Application filed October 20, 1905. Serial No. 283,680.

To all whom it may concern:

Be it known that I, ORRELL ASHTON, a citizen of the United States, residing at Lawrence, in the county of Essex and Commonwealth of Massachusetts, have invented certain Improvements in Assembling-Machines, of which the following description, in connection with the accompanying drawings, is a specification, like reference characters on the drawings indicating like parts in the several figures.

This invention relates to assembling machines for use in the manufacture of boots and shoes, and more particularly to machines for facilitating the assembling of parts of boots and shoes preliminary to pulling over and lasting.

Heretofore, in the manufacture of boots and shoes, so far as I am aware, no provision has been made for insuring that parts such as a counter, innersole and lined upper will be assembled in proper relation for the pulling-over operation. It is desirable that these parts be secured together in a proper manner, for if they are assembled in an incorrect relation it may be difficult or impossible to cure the defect in subsequent operations.

My invention is concerned more particularly with the provision of means for facilitating assembling of parts, such as those mentioned, in a correct relation. It is particularly desirable in assembling these parts that the counter and upper be held closely against the edge of the innersole at its extreme heel end before they are secured to the innersole.

An important feature of the invention consists in means for forcing upper and counter against the end of the innersole and for holding them in close contact therewith while they are being secured to the innersole.

The machine herein described comprises a support for the parts to be assembled. Preferably, the parts are assembled on the last upon which the boot or shoe is to be lasted. I have accordingly shown herein a last support arranged to sustain a last in an inverted position with its bottom face approximately horizontal, the construction being such that an innersole may be loosely superposed on said face. Clamping mechanism is provided to act upon the heel end of the last, and to hold the upper and counter closely against the heel end of the innersole. The last support is preferably a vertically arranged pivot

pin, arranged to enter the heel of the last. The clamping mechanism is constructed to hold the last from movement upon the pivot pin when brought into operative relation to the last.

Other features of the invention will be hereinafter described and defined in the claims.

In the accompanying drawings:—Figure 1 is a side elevation with parts in section of a machine constructed according to this invention. Fig. 2 is a plan of Fig. 1 with the last removed from its support, and Fig. 3 is a longitudinal vertical section of a portion of the machine illustrated in Figs. 1 and 2 showing the parts in operative position.

A suitable standard 1 is provided to support the last in horizontal position. The standard is fitted with a last pin 2 which enters the usual pin hole in the heel part of the last, and thus pivotally supports the last. Upon the base 3, which forms the lower part of the standard 1, upwardly projecting lugs 4 are provided which are perforated to receive and support rotatably a shaft 5. The shaft 5 carries a sleeve 6, placed between the upwardly projecting lugs 4 and firmly attached to the shaft in any suitable way. The sleeve 6 is provided with arms 7 and 8, the arm 7 being connected with a treadle 10 by a chain 9 or its equivalent while the arm 8 carries a work-engaging device forming an important feature of the invention.

The work-engaging device which is illustrated comprises a clamping member 11 carried on the upper end of the arm 8. The acting face of the member 11 is preferably curved as shown in Fig. 2, so as to embrace the heel end of the last. In the movement of the member 11 against the last, the concave face of said member tends to center the heel end of the last with relation to said face and the engagement of said concave face with the last holds the last from swinging about the pivot pin 2. A convenient means for supporting the member 11 on the arm 8 comprises a slotted bar 12 adjustably held on the upper end of arm 8 by a set screw 13. The clamping member 11 is pivotally carried on the slotted bar 12 by a headed bolt 14 which projects through openings in the clamping member 11 and bar 12 and is engaged by a nut 15. The opening in the bar 12 in which the bolt 14 is inserted may be internally threaded if desired, so that the bolt 14 may

be screwed into position, the nut 15 serving as a lock-nut to retain said bolt in the position to which it is adjusted. The member 11 is supported with its acting face in position 5 to engage the work when the arm 8 is swung towards the last, and the movement of said arm is limited by contact of said member with the work. To hold the member 11 in position a flat headed plunger 16 may be provided which is held against a flattened face on the member 11 by a spring 17. It will be seen that in the arrangement shown the plunger 16 tends to hold the member 11 with its acting face in approximately correct position 10 to bear on the work when said member is moved towards the last. It will also be seen that the member 11 is yieldingly controlled so that when forced against the work it may automatically move about its pivot as 15 indicated in Fig. 3, to assume that position in which it bears evenly on the work. To move the clamping member away from the work means may be provided tending to hold the arm 8 in the position shown in Fig. 20

25 1. The means shown comprise a coiled spring 18 surrounding the shaft 5, and connected at one of its ends to any fixed part of the machine, as for example one of the lugs 4 which carry the shaft 5. The other end of 30 the spring may be attached to a ring 19 which is adjustably held on the shaft 5, by a set screw 20. By the adjustment of the ring 19 the inactive position of the arm 8 may be varied.

35 In the preferred mode of use of the machine shown, a counter 24 is inserted between lining 22 and upper 21 and arranged approximately centrally of the heel. A last is placed within the lined upper and supported upon the pin 2, in an inverted position. An innersole 23 is placed loosely upon the last, with its heel edge between the last and the lining. The parts being in substantially the position shown in Fig. 1, the clamping member 11 is brought against the work, 40 forcing upper and counter closely against the edge of the innersole, and holding them in that position while a tack 25 is driven through upper, counter, lining and innersole 45 preferably at the extreme rear of the heel.

Having fully described my invention what I claim as new and desire to secure by Letters Patent is:-

50 1. A machine for assembling parts of boots and shoes preliminary to lasting, comprising a last pivot arranged to support a last normally for free pivotal movement in an approximately horizontal plane, and clamping mechanism arranged to hold the upper 55 against the last at the heel and to hold the

last simultaneously from movement upon said pivot.

2. A machine for assembling parts of boots and shoes preliminary to lasting, comprising a last pivot arranged to support a last normally for free pivotal movement in an approximately horizontal plane, and a clamp sustained to be movable towards and from 65 said pivot and having an acting face concave to receive the heel end of the last, said clamp in its acting position being held from lateral movement whereby said last is rigidly held upon its pivot.

3. A machine for assembling parts of boots and shoes preliminary to lasting, comprising 75 a stationary last pivot arranged to support a last normally for free pivotal movement in an approximately horizontal plane, and clamping mechanism arranged to hold the upper against the last at the heel and to hold the 80 last simultaneously from movement upon said pivot.

4. An assembling machine, comprising a stationary vertical last pin, arranged to support a last pivotally in an approximately 85 horizontal position, an arm pivotally supported to move in a vertical plane, a clamp carried by said arm, means tending to hold said arm in a position removed from the last pin, and mechanism for actuating said arm 90 to hold the clamp against the last supported upon the last pin.

5. A machine for assembling parts of boots and shoes preliminary to lasting, comprising a vertical last pivot arranged to support a 95 last normally for free pivotal movement, a clamp sustaining member arranged for movement toward and from said last pivot, and a clamp having a rigid work engaging face and arranged for free movement about a horizontal axis upon said member. 100

6. A machine for assembling parts of boots and shoes preliminary to lasting, comprising a vertical last pivot arranged to support a last normally for free pivotal movement, a 105 clamp sustaining member arranged for movement toward and from said last pivot, a clamp having a rigid work engaging face and arranged for free movement about a horizontal axis upon said member, and means 110 for maintaining the clamp normally in a predetermined position upon said member.

In testimony whereof I have signed my name to this specification in the presence of two subscribing witnesses.

ORRELL, ASHTON.
